ABSTRACT

A quick change hinge assembly for pivotally coupling members. A pair of hinge blocks mounted to a fixture have laterally extending pivot pins. A first member having laterally extending sockets with entry slots is pivotally mounted to a pair of the inwardly extending pins mounted to the hinge blocks. A second member is pivotally mounted to the outwardly extending pivot pins mounted to the hinge blocks. Another embodiment has horizontally spaced hinged blocks mounted to a fixture with the hinge blocks having laterally extending sockets. A first member has outwardly extending pivot pins received in the sockets whereas a second member has inwardly extending pivot pins received in the sockets. A third embodiment has a pair of hinge blocks with laterally extending sockets and entry slots pivotally receiving pivot pins mounted to a first member. Additional pins are mounted to the first member and extend outwardly into laterally extending sockets and entry slots of a second member. In the preferred embodiment, the first and second members are pivotally mounted to a single pin which is removably mounted to a pair of spaced apart and unconnected hinge blocks. The pin has crescent shaped portions received by laterally extending sockets and channels of the members.

QUICK CHANGE HINGE ASSEMBLY

CROSS-REFERENCE TO RELATED APPLICATION

This application is a continuation-in-part of my U.S. Pat. application Ser. No. 123,741 of the same title and filed on Mar. 12, 1971.

BACKGROUND OF THE INVENTION

1. Field of the Invention

This invention is in the field of hinges.

2. Description of the Prior Art

A number of hinges have been devised for pivotally coupling a plurality of members. A representative sample of the prior art includes the following disclosures:

U.S. Pat. No. 3,557,393 issued to Waldon
 U.S. Pat. No. 1,496,466 issued to Jackson
 U.S. Pat. No. 2,240,220 issued to Leslie
 U.S. Pat. No. 2,333,732 issued to Morris
 U.S. Pat. No. 2,500,594 issued to Young
 U.S. Pat. No. 3,038,173 issued to Turek et al.
 U.S. Pat. No. 3,063,063 issued to Brooks
 U.S. Pat. No. 3,261,029 issued to Beneke, Jr.
 U.S. Pat. No. 3,471,874 issued to Dixon
 British Pat. No. 922,795 issued to Ideal-Standard Limited

The quick change hinge assemblies disclosed herein allow for quicker and easier coupling of members than the hinge assemblies disclosed in the aforementioned Letters Patent. My hinge assemblies have crescent shaped pivot pins which will either snap into or out of the entry slots and sockets when placed under stress in lieu of breaking the pin receivers.

SUMMARY OF THE INVENTION

One embodiment of the present invention includes a quick change hinge assembly comprising a pair of hinge blocks securable to a fixture, pin means mounted to the blocks, a first and second member pivotally mounted to the pin means with the first member having a pair of sockets and the second member having a pair of channels. The pin means project into the sockets and channels both of which have pin entry slots enabling the members to be removed without removing the hinge blocks or pins from the fixture.

It is an object of the present invention to provide a quick change hinge assembly which allows relatively quick and easy coupling of members.

Yet another object of the present invention is to provide a hinge assembly having crescent shaped pivot pins which are relatively stronger than the prior art pivot pins and which will either snap into or entirely out of slots rather than breaking the pin receivers.

In addition, it is an object of the present invention to provide a new and improved hinge assembly for pivotally coupling a lid and ring to a toilet bowl.

Related objects and advantages of the present invention will be apparent from the following description.

BRIEF DESCRIPTION OF THE DRAWINGS

FIG. 1 is a top view of toilet members embodying the present invention.

FIG. 2 is a side elevational view thereof.

FIG. 3 is an end view looking in the direction of arrow 3 of FIG. 2 illustrating details of the hinge construction.

FIG. 4 is a fragmentary cross-sectional view taken along a line and viewed in the direction of arrows 4-4 of FIG. 3.

FIG. 5 is a fragmentary cross-sectional view taken along a line and viewed in the direction of arrows 5-5 of FIG. 3.

FIG. 6 is a fragmentary cross-sectional view taken along a line and viewed in the direction of arrows 6-6 of FIG. 3.

FIG. 7 is a fragmentary cross-sectional view taken along a line and viewed in the direction of arrows 7-7 of FIG. 3.

FIG. 8 is the same view as FIG. 6 only showing an alternate pin.

FIG. 9 is the same view as FIG. 7 only showing an alternate pin. FIG. 10 is the same view as FIG. 3 only showing the second embodiment of the present invention.

FIG. 11 is a fragmentary cross-sectional view taken along a line and viewed in the direction of the arrows 11-11 of FIG. 10.

FIG. 12 is a fragmentary cross-sectional view taken along a line and viewed in the direction of the arrows 12-12 of FIG. 10.

FIG. 13 is a fragmentary cross-sectional view taken along a line and viewed in the direction of arrows 13-13 of FIG. 10.

FIG. 14 is the same view as FIG. 11 only showing an alternate pin.

FIG. 15 is the same view as FIG. 13 only showing an alternate pin.

FIG. 16 is the same view as FIG. 3 only showing a third embodiment incorporating the present invention.

FIG. 17 is a fragmentary cross-sectional view taken along a line and viewed in the direction of arrows 17-17 of FIG. 16.

FIG. 18 is a fragmentary cross-sectional view taken along a line and viewed in the direction of arrows 18-18 of FIG. 16.

FIG. 19 is a fragmentary cross-sectional view taken along a line and viewed in the direction of arrows 19-19 of FIG. 16.

FIG. 20 is a fragmentary cross-sectional view taken along a line and viewed in the direction of arrows 20-20 of FIG. 16.

FIG. 21 is a diagram illustrating the removal of a crescent shaped pin from a socket.

FIG. 22 is a cross-sectional view similar to FIG. 18 only showing the double sided pin.

FIG. 23 is a cross-sectional view similar to FIG. 20 only showing the double sided pins.

FIG. 24 is an end view looking in the same direction as FIG. 3 only showing the preferred embodiment of the present invention.

FIG. 25 is a fragmentary cross-sectional view taken along a line and viewed in the direction of arrows 25-25 of FIG. 24.

FIG. 26 is a fragmentary cross-sectional view taken along a line and viewed in the direction of arrows 26-26 of FIG. 24.

FIG. 27 is a fragmentary cross-sectional view taken along a line and viewed in the direction of arrows 27-27 of FIG. 24.

FIG. 28 is a fragmentary cross-sectional view taken along a line and viewed in the direction of arrows 28—28 of FIG. 24.

FIG. 29 is a side view of mounting member 207 viewed in the same direction as FIG. 27 with the pin removed.

FIG. 30 is a perspective view of the pin shown in FIG. 24.

DESCRIPTION OF THE PREFERRED EMBODIMENTS

For the purposes of promoting an understanding of the principles of the invention, reference will now be made to the embodiments illustrated in the drawings and specific language will be used to describe the same. It will nevertheless be understood that no limitation of the scope of the invention is thereby intended, such alterations and further modifications in the illustrated device, and such further applications of the principles of the invention as illustrated therein being contemplated as would normally occur to one skilled in the art to which the invention relates.

Referring now to FIGS. 1 and 2, there is shown a toilet seat ring 31 and a toilet seat lid 30 pivotally mounted atop flange 32 of a conventional toilet. A quick change hinge assembly allows for the quick and easy removal of the ring and lid from flange 32. FIG. 3 is an end view looking in the direction of arrow 3 of FIG. 2 showing the first embodiment of the quick change hinge assembly. A pair of bosses or hinge blocks 34 and 35 are horizontally spaced apart and integrally mounted to the horizontal plate 33 secured to the toilet bowl flange. A variety of means may be utilized to secure plate 33 to the flange of the toilet. For example, a plurality of studs 50 (FIG. 2) may be connected to plate 33 so as to extend freely through flange 32 being threadedly received by hexagonally shaped nuts thereby securing the plate to the toilet bowl flange. The heads of studs 50 may be concealed within plate 33 so as to not be visible. A pair of pins 36 and 37 are cantileveredly mounted to hinge block 34 and a second set of pins 38 and 39 are cantileveredly mounted to block 35. The pins extend into sockets formed in ring 31 and lid 30.

Ring 31 extends between hinge blocks 34 and 35 and has a first recess 47 and a second recess 48 for respectively receiving blocks 34 and 35. FIG. 4 is a cross-sectional view taken along a line and viewed in the direction of arrows 4—4 of FIG. 3 illustrating recess 47. The recess is defined by sidewall 49 and lip 67. Socket 44 is located on wall 49 having a sidewall 52 with a substantially cylindrical bearing surface. A similar socket is provided in ring 31 for receiving pin 38 of block 35. An entry slot 54 opens into socket 44 through side wall 52 with the width denoted by item 57 being smallest at the opening into socket 44. A similar entry slot is shown in FIG. 3 opening into socket 45 for receiving pin 38. Lip 67 and lip 68 extend upwardly from ring 31 around blocks 34 and 35 so as to conceal the blocks when viewed looking downwardly from the front of the toilet ring and lid.

Toilet lid 30 has a pair of ears 40 and 41 positioned outwardly and adjacent respectively blocks 34 and 35. Ears 40 and 41 have sockets 42 and 43 located thereon for receiving pins 36 and 39. FIG. 5 is a cross-sectional view of lid 30 showing ear 40 having a side wall 56 with socket 42 located thereon. An entry slot 55, identical

to the entry slot previously described, opens into socket 42 with the width of the opening being denoted by item 58. Socket 42 has a side wall 53 of a general cylindrical configuration providing a bearing surface for contacting pin 36. Each 41 has a similar socket 43 and entry slot to that just described for ear 40.

A variety of different shaped pins may be secured to blocks 34 and 35 for providing a bearing surface for the pivotal mounting of lid 30 and ring 31. One such pin is shown in FIGS. 6 and 7. FIG. 6 is a cross-sectional view taken along a line and viewed in the direction of arrows 6—6 showing pin 37 mounted to side 74 of block 34. FIG. 7 is a similar view only showing pin 36 mounted to side 75 of block 34. Pin 37 will now be described it being understood that a similar description applies to pins 36, 38 and 39. Pin 37 has a concave surface 65 and a convex surface 66. Convex surface 66 forms a rounded bearing surface 51 for contacting wall 52 of socket 44. The thickness 59 of pin 37 across convex surface 66 is greater than the width 57 of entry slot 54 at the location where the slot opens into socket 44. Thus, lid 30 and ring 31 are prevented from disengaging the pins until the lid and ring are oriented in such a manner so as to allow removal.

FIG. 21 illustrates the removal of the crescent shaped pin from the sockets of FIG. 3 or from the mounting blocks to be described later in this specification. The pin in the fully seated position 76 is completely contained within the socket. The pin and the socket are then moved apart so as to allow edge 79 to follow the concave surface 80 of the pin. The pin and socket are then moved further apart until the pin is completely disengaged from the socket as shown in position 77. Of course, the pin and socket must first be rotated so as to allow edge 79 to follow the concave surface of the pin. This rotational motion between the pin and socket is caused by rotating the lid 30 and/or ring 31. Pins 36, 37, 38 and 39 are aligned so as to define axis 46 about which lid 30 and ring 31 are pivotable. Lid 30 is pivoted in the direction of arrow 71 to the dashed line position 72 (FIG. 5) in order to remove the lid from pins 36 and 39. The lid is then pulled upwardly so as to disengage the pin from the socket of ears 40 and 41 in the manner previously described and illustrated in FIG. 21. Ring 31 may then be removed by pivoting the ring about axis 46 in the direction of arrow 73 (FIG. 4) and then pulled upwardly in order to disengage pins 37 and 38 from the sockets of ring 31. Ring 31 is removed in a manner identical to the removal of lid 30. It is understood that a single pin extending through the sides of block 34 may be utilized in lieu of a pair of pins 36 and 37. Likewise, it is understood that a single pin projecting through both sides of block 35 would perform the same functions as the pair of pins 38 and 39. It is to be noted that the entry slots of sockets 42, 43, 44 and 45 are aligned and opened in the same direction when lid 30 is positioned atop ring 31 as shown in FIG. 3. The concave surfaces of all of the pins open in the same direction. The substantially cylindrical surfaces for the pins and sockets allow for pivoting of lid 30 and ring 31 about axis 46. In addition, the entry slots of sockets 42, 43, 44 and 45 interrupt the generally cylindrical surfaces of the sockets extending radially outward from the cylindrical surfaces. Likewise, the cylindrical surfaces of the pins 36, 37, 38 and 39 are interrupted by the concave surface 65 which may also be considered an elongated groove having a length coextensive with

the portion of the pins received in the entry slots. The chords 69 (FIG. 5) which extend across each socket's cylindrical surface at the opening of the entry slot and the chord 70 (FIG. 7) of the cylindrical surface of each pin which extends across the concave surface are both such as to accommodate removal of the pins from the sockets in a direction transverse to the direction of axis 46 in only two relative rotational positions of lid 30 and ring 31. That is, lid 30 and ring 31 may be disengaged from the pins only when the lid and ring are in a substantially vertical position. Thus, the lid and ring may be pivoted upward to a vertical position with the ring being removed first or with the lid and ring being removed simultaneously. The toilet bowl shown in FIG. 2 in dashed lines prevents and acts as a stopping means to prevent the lid and ring from being pivoted downward to a substantially vertical position for removal of the pins from the sockets. Thus, the toilet bowl is a stopping means which limits relative rotation between the lid and ring and precludes the attainment of the downwardly vertical position.

An alternate pin is shown in FIGS. 8 and 9 and may be utilized in lieu of the crescent shaped pins of FIGS. 6 and 7. The pin shown in FIGS. 8 and 9 has a pair of parallel spaced apart flat sides 61 and 62 which are spaced apart a distance not greater than widths 57 or 58. The flat sides are joined on both ends by a pair of rounded oppositely facing sides 63 and 64 which are spaced apart a distance 60 greater than widths 57 or 58. The lid and ring must be pivoted to the upward vertical position for allowing the flat sided pins to be removed from the sockets.

The second embodiment of the quick change hinge assembly is illustrated in FIG. 10 which is similar to the view of FIG. 3. The distinguishing feature between FIGS. 3 and 10 is that the pins are mounted to lid 30 and ring 31 in FIG. 10 in lieu of to the hinge blocks 34 and 35 as shown in FIG. 3. Therefore, the sockets are provided in the hinge blocks to receive the pins. A pair of horizontally spaced upstanding mounting bosses or hinge blocks 100 and 101 are identical each having laterally extending sockets with entry slots opening into the sockets. FIG. 12 is a cross-sectional view viewed in the direction of arrows 12-12 of FIG. 10 illustrating mounting block 100. Block 100 will now be described it being understood that a similar description applies to block 101. Block 100 has a socket 106 and entry slot 107 similar to that previously described for the socket and entry slot of ears 40 and 41, the exception being that the entry slot opens vertically upward in lieu of the horizontal opening shown in FIG. 3. The socket and entry slot extend completely through mounting block 100 and receive pin 102 cantileveredly mounted to lid 30 and pin 103 cantileveredly mounted to ring 31. Pin 102 is mounted to ear 40 of lid 30 whereas pin 105 is mounted to ear 41 of lid 30. Ring 31 extends between blocks 100 and 101 in a manner similar to blocks 34 and 35. Likewise, ears 40 and 41 are spaced apart outwardly and adjacent blocks 100 and 101. Ring 31 has a pair of lips 67 and 68 previously described and illustrated in FIG. 3 which extend upward partially around blocks 100 and 101. Lips 67 and 68 thereby form recesses 47 and 48 and extension 108 which is positioned between the hinge blocks. Pins 102 through 105 extend only partially through the sockets thereby allowing independent rotation of ring 31 with respect to lid 30 and

vice versa. As previously described, lips 67 and 68 are positioned over and conceal the hinge blocks.

Pins 102 through 105 are identical with respect to pins 36 through 39 with the exception that the concave surfaces 109 (FIG. 13) open vertically and upward in lieu of horizontally when the lid and ring are positioned horizontally. The concave surfaces 109 of the crescent shaped pins are aligned whenever the lid 30 abuts ring 31. The lid and ring must be pivoted to the upward vertical position since the entry slots open upwardly. As previously described for pins 36 through 39, pins 102 through 105 have substantially cylindrical surfaces which contact the cylindrical surfaces of the sockets with the concave surfaces of the pins extending laterally along the lengths of the pins. The axis of rotation 46 of lid 30 and ring 31 extends through the centers of pins 102 through 105.

FIGS. 14 and 15 show an alternate double sided pin identical to the pins previously shown and described in FIGS. 8 and 9 with the exception that the flat sides of pins 110 and 111 are horizontal when the lid and ring are horizontal. Pins 110 and 111 would replace pins 102 and 103 with pins identical to pins 110 and 111 also replacing pins 104 and 105. Pin 110 has a pair of flat sides spaced apart a distance not greater than the width of an entry slot opening into a socket whereas the rounded sides of pin 110 are spaced apart a distance greater than the width of the slot opening into a socket. Likewise, the pins and entry slots of the second embodiment are arranged so as to allow removal of the pins from the sockets only when the lid and ring are in a substantially vertical position.

The third embodiment of the quick change hinge assembly is illustrated in FIG. 16 and is substantially different from the first two embodiments of the hinge assembly. In the third embodiment, the hinge blocks 140 and 141 have sockets and entry slots similar to the second embodiment and receive pins having both ends attached to ring 146. In addition, the ring has a pair of cantileveredly mounted outwardly extending pins which are received in sockets provided in ears 40 and 41 of lid 30. The horizontally spaced upstanding blocks 140 and 141 are integrally mounted and interconnected to plate 33. Each block has a laterally extending socket with an entry slot identical to that described for blocks 100 and 101. Thus, this specification will not elaborate further on the sockets and entry slots of blocks 140 and 141. A pair of inner pins 142 and 143 are secured to ring 146 extending completely through the sockets of blocks 140 and 141 and across recesses 144 and 145 of ring 146 which respectively receive blocks 140 and 141. The pair of inner pins extend completely across these recesses and are crescent shaped or have flat sides as previously described for the first two embodiments. Each end of inner pin 142 and each end of inner pin 143 are fixedly connected to ring 146.

Recesses 144 and 145 form an extension 147 which extends between blocks 140 and 141 and a pair of flanges 148 and 149 which are positioned outwardly adjacent blocks 140 and 141. Blocks 140 and 141 are concealingly received by extension 147 whereas the extension 147 is concealingly received between ears 40 and 41 and lid 30 when viewed above and in front of the lid.

A pair of outer pins 150 and 151 are cantileveredly mounted to flanges 148 and 149 projecting outwardly into the laterally extending sockets formed in ears 40

and 41. Thus, lid 30 is pivotally mounted on pins 150 and 151 whereas ring 146 is pivotally mounted by pins 142 and 143 on blocks 140 and 141. The size and configuration of pins 142, 143, 150 and 151 is identical to the pins previously described for the embodiment shown in FIG. 3 as well as for the embodiment shown in FIG. 10. The concave surface 152 (FIG. 17) of pins 150 and 151 opens horizontally to the rear of the toilet when the lid and ring are horizontally positioned and are symmetrical about horizontal axis 154. The concave surface 153 if pins 142 and 143 open upwardly when ring 146 is positioned horizontally atop the toilet bowl. Concave surfaces 153 are symmetrical about vertical axis 155 which is angularly positioned 90° with respect to horizontal axis 154. Thus, the concave surfaces of pins 142 and 143 are angularly positioned 90° with respect to the concave surfaces 152 of pins 151 and 150. It is also to be noted that the cylindrical surfaces of all sockets and crescent shaped pins subtend an angle greater than 180°.

The third embodiment also includes a quick change hinge assembly utilizing flat sided pins in lieu of the crescent shaped pins 142, 143, 150 and 151. These flat sided pins are shown in FIGS. 22 and 23 and are identical to the flat sided pins previously described and illustrated in the first and second embodiments. Two outer flat sided pins 157 (FIG. 22) are respectively cantileveredly mounted to flanges 148 and 149 (FIG. 16) projecting into the laterally extending sockets formed in ears 40 and 41. The flat sides of pins 157 are positioned vertically when ring 146 is in a horizontal position. Two inner flat sided pins 156 (FIG. 23) are mounted to ring 146 extending across recesses 144 and 145 and through the laterally extending sockets of blocks 140 and 141. The flat sides of pins 156 are horizontally positioned when ring 146 is in a horizontal position. Thus, to remove lid 30, the lid must be rotated to a vertical position with ring 146 remaining in a horizontal position. To remove ring 146 from blocks 140 and 141, the ring must be pivoted to a vertical position. The parallel flat sides of pins 156 and 157 are spaced apart a distance not greater than the width of the entrance slots opening into the sockets. In addition, the pair of oppositely facing rounded sides of the flat sided pins are spaced apart a distance greater than the width of the entrance slot opening into the sockets.

Shown in FIG. 24, is the preferred embodiment of the invention and includes a first and second adjacent member 201 and 202 which are pivotally and removably mounted atop a toilet bowl fixture 203. Member 201 is a toilet lid whereas member 202 is a toilet seat ring. The preferred embodiment is similar to the embodiment shown in FIGS. 3 through 9 with the major exception that a single pivot pin 204 is utilized to mount the members to a pair of spaced apart and unconnected hinge blocks 207 and 208.

Pin 204 (FIG. 30) has a main cylindrical body 205 with a pair of discs 209 and 210 integrally mounted thereto and arranged perpendicularly to pivot axis 206 which extends centrally through the pin. The pin has opposite ends 211 and 212 extending outward from discs 209 and 210 with each end having a crescent cross section. In addition, the portions 213 and 214 immediately inward of discs 209 and 210 have crescent cross sections.

Each hinge block 207 and 208 is separate and includes a base 215 (FIG. 29) upon which upstanding

boss 216 is mounted. Each boss has a crescent shaped channel 217 through which pin 204 projects with channels 217 extending horizontally and being complementary in size and shape to ends 211 and 212 thereby preventing rotation of the pin with respect to the hinge blocks. The mutually opposed faces 218 and 219 (FIG. 24) of hinge block 207 and 208 each have a counterbore recess 220 (FIG. 29) adjacent to and surrounding channels 217. Discs 209 and 210 extend respectively into the recesses 220 of blocks 207 and 208 thereby preventing axial movement of the pin with respect to the hinge blocks. Hinge blocks 207 and 208 are secured to fixture 203 by fasteners 221 which extend downwardly from bases 215 and into the fixture. Bases 214 may be provided with a counterbored through hole at the end opposite bosses 216 with the head of the fasteners being received in the counterbored holes. Mounting pads of a material such as rubber are secured to the bottom surfaces of the bases by adhesives. Bosses 216 are positioned at the ends of bases 215 with the bases extending outwardly away from the members 201 and 202. The concave portion of the pin opens toward members 201 and 202, toward the front of the toilet bowl and away from fasteners 221.

Members 201 and 202 are similar to members 30 and 31 of FIG. 3. Member 201 has a pair of spaced apart and mutually opposed flanges 222 and with each flange having a socket into which pin 204 projects. Socket 223 will now be described it being understood that a similar description applies to socket 224. Socket 223 (FIG. 25) is defined by a side wall 227 which contacts the convex bearing surface of end 211 of pin 204 (FIG. 30). A pin entry slot 225 opens through side wall 227 allowing pin 204 to pass therethrough for removal of member 201 from the assembly. The convex bearing surfaces of ends 211 and 212 are cylindrical and are interrupted each by a separate elongated groove which forms the concave portion of the crescent cross section. The crescent cross section present at ends 211 and 212 and portions 213 and 214 has a maximum diameter 228 (FIG. 30) which is greater than the widths 226 of the pin entry slots 225 as the slots open into the sockets 223 and 224. Likewise, diameter 228 is greater than the widths 229 of the entry slots 230 (FIG. 28) as the slots open into sockets 231 and 232 provided respectively in flanges 223 and 234 (FIG. 24) of member 202. The major diameter 228 of pin body 205 is constant throughout the length of the pin with the exception of the diameter of discs 209 and 210.

Referring to FIG. 21, the pin shown there can represent pin 204 with the socket representing sockets 223 and 224 and pin entry holes 231 and 232. The crescent shape of the pin is such so as to allow removal of members 201 and 202 from the pin when the members are oriented in a specific manner. The crescent cross section has a dimension from the concave to the convex surface thereof which is not greater than the widths 226 and 229 of the pin entry slots into the sockets 223 and 224 and pin entry holes 231 and 232.

The crescent cross section of the pin has pairs of parallel tangent lines with the spacing between tangent lines on the concave and convex surface not greater than the width of the slots. For example, lines 242 and 243 are respectively tangent to points 240 and 241 on the convex and concave surfaces of the pin. The distance 244 between the parallel tangent lines is not greater than the width 250 of the pin entry slot into the

hole or socket receiving the pin. Likewise, the maximum distance 249 between lines 247 and 248 respectively tangent to point 245 and 246 on the convex and concave surface of the pin is not greater than the width 250. Thus, the maximum distance from tangent lines of each of the outboard convex surfaces of ends 211 and 212 which are parallel to tangent lines of their respective grooves is not greater than the widths 226 (FIG. 25) of the first pin entry slots at the sockets to accommodate removal of member 201 from pin 204 in a direction transverse to the direction of pivot axis 206 beginning in only two relative rotational positions from the first member. Likewise, the maximum distance from tangent lines each of which is tangent to the inboard convex surfaces of portions 213 and 214 which are parallel to tangent lines of their corresponding channels is not greater than the widths 229 of the pin entry slots 230 at the pin entry holes to accommodate removal of member 202 from pin 204 in a direction transverse to the direction of pivot axis 206 beginning on only two relative rotational positions of member 202.

The convex surfaces of ends 211 and 212 are outboard of the hinge blocks and are interrupted by the elongated groove formed by the concave surface. Likewise the inboard bearing surfaces are the convex surfaces of portion 213 and 214 positioned between the hinge blocks and which are interrupted by an elongated channel. The outboard surfaces and the inboard surfaces subtend angles in excess of 180°. Each groove and channel are aligned and face in the same direction. The lengths of the elongated channels of portions 213 and 214 are co-extensive with the portion of the pin received in the pin entry holes 231 and 232.

The hinge blocks 207 and 208 are positioned between flanges 222 and flanges 223 and 234. A pair of curved lips 252 and 253 are integrally connected to member 202 and extend upwardly and concealingly around the bosses of hinge blocks 207 and 208. Curved lips 252 and 253 are integrally joined together by curved wall 254 which extends upwardly over the top of pin 204. Likewise, member 201 has a curved wall 255 which extends between and connects flanges 222 and also extends upwardly with and over curved lips 252 and 253. The pin entry slots of members 201 and 202 are aligned and open in the same direction when the member 201 rests atop member 202 in a horizontal position. Fixture 203 extends beneath hinge blocks 207 and 208 limiting pivotal movement of members 201 and 202 and precluding attainment of one of the two relative rotational positions. Fixture 203 is the toilet bowl and has a fixed location with respect to the bosses of hinge blocks 207 and 208 and is engageable with member 202. The members may be removed by positioning the members only in the vertical upward position.

While the invention has been illustrated and described in detail in the drawings and foregoing description, the same is to be considered as illustrative and not restrictive in character, it being understood that only the preferred embodiment has been shown and described and that all changes and modifications that come within the spirit of the invention are desired to be protected.

The invention claimed is:

1. A quick change hinge assembly comprising:

a pair of spaced apart upstanding hinge blocks securable to a fixture; circular pin means defining a single pivot pin with a radius, said pin being mounted to said blocks and including a pair of outboard rounded bearing surfaces positioned outboard of said blocks and a pair of inboard rounded bearing surfaces positioned between said blocks, each of said outboard bearing surfaces are cylindrical and are interrupted each by a separate elongated groove located outward of said blocks, each of said inboard bearing surfaces are cylindrical and are interrupted each by a separate elongated channel located inward of said blocks, each groove and each channel being a completely radially formed concave surface with each concave surface subtending an angle in excess of 90° with said angle being defined and included between opposite intersecting outermost tangent lines to said concave surface providing a crescent shaped pin cross section at each groove and each channel; and,

a first member and a second adjacent member removably and pivotally mounted to said pin means about said axis, said first member being a toilet seat lid having a pair of spaced apart and mutually opposed flanges having sockets into which said pin means project, said sockets having walls contacting said outboard bearing surfaces and having first pin entry slots opening through said walls allowing said pin means to pass therethrough for removal of said first member, and, said second member being a toilet seat ring having flange means including oppositely facing surfaces, pin entry holes located on said oppositely facing surfaces and sidewalls defining said holes and bearingly receiving said inboard bearing surfaces, said flange means including second pin entry slots opening through said side walls allowing said pin means to pass therethrough for removal of said second member.

2. The assembly of claim 1 wherein:

the maximum distance between tangent lines of each of said outboard bearing surfaces which are parallel to tangent lines at the maximum depth of their corresponding groove is not greater than the widths of said first pin entry slots at said sockets to accommodate removal of said first member from said pin means in a direction transverse to the direction of said pivot axis beginning in only two relative rotational positions of said first member.

3. The assembly of claim 2 wherein:

each separate elongated channel has a length coextensive with the portion of said pin means received in said holes;

the maximum distance between tangent lines of each of said inboard bearing surfaces which are parallel to tangent lines at the maximum depth of their corresponding channel is not greater than the widths of said second pin entry slots at said holes to accommodate removal of said second member from said pin means in a direction transverse to the direction of said pivot axis beginning in only two relative rotational portions of said second member.

4. The assembly of claim 3 wherein:

said outboard bearing surfaces and said inboard bearing surfaces subtend angles in excess of 180°.

5. The assembly of claim 4 wherein: each of said hinge blocks has a boss;

11

said second member has a pair of curved lips extending upwardly and concealingly around said bosses,

said first member has a curved wall extending between and connecting said flanges which extends upwardly with and over said curved lips. 5

6. The assembly of claim 5 wherein: said first pin entry slots and said second pin entry slots are aligned and open in the same direction when said first member rests atop said second member;

each groove and each channel are aligned and face in the same direction;

said fixture extends beneath said bosses limiting pivotal movement of said first and second member and precluding attainment of one of said two relative rotational positions; 15

said fixture is a toilet bowl, said toilet bowl has a fixed location with respect to said bosses and is engageable by said ring and said lid to preclude attainment of one of said two relative rotational positions. 20

7. The assembly of claim 6 wherein:

each groove and each channel open toward the front of said toilet bowl.

8. The assembly of claim 1 wherein:

said hinge blocks each have a horizontally extending channel through which said single pin projects. 25

9. The assembly of claim 8 wherein:

each of said hinge blocks are separate and are not in-

tegrally connected together, said blocks have mutually opposed faces with recesses thereon adjacent each pin channel,

said pin has a pair of projections of diameter larger than said pin extending into said recesses preventing axial movement of said pin.

10. The assembly of claim 9 wherein:

said projections are discs integrally mounted on said pin perpendicular to said pivot axis, said recesses in said opposed faces are counterbores which receive said discs.

11. The assembly of claim 9 wherein:

said pin at said pin crescent shaped cross section is received by each hinge block channel each of which is crescent shaped preventing rotational movement therebetween.

12. The assembly of claim 11 wherein:

said crescent cross section of said pin has a maximum diameter greater than the widths of said first pin entry slots at said sockets and the widths of said second pin entry slots at said holes, said crescent cross section of said pin having a dimension from the concave to the convex surfaces thereof not greater than said widths of said first slots and said widths of said second slots allowing said first and second member to be removed from said pin.
